CLAIM

The ornamental design for a blackhead remover, as shown and described.

DESCRIPTION

FIG. 1 is a front and bottom perspective view of a blackhead remover showing my new design;

FIG. 2 is a rear and top perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an enlarged view of the blackhead remover taken from detail 9 in FIG. 8.

The dash-dot-dash lines encircling the enlargement forms no part of the claimed design. The broken lines illustrate portions of the blackhead remover that form no part of the claimed design.
